UNITED STATES PATENT OFFICE.

GIULIO SILVESTRI, OF VIENNA, AUSTRIA-HUNGARY

APPARATUS FOR DRIVING ROTARY ENGINES.

1,227,967.

Specification of Letters Patent.

Patented May 29, 1917.

Application filed June 16, 1913. Serial No. 774,002.

To all whom it may concern:

Be it known that I, GIULIO SILVESTRI, a citizen of Austria, and resident of Vienna, in the Province of Lower Austria and Empire of Austria-Hungary, have invented certain new and useful Improvements in Apparatus for Driving Rotary Engines, of which the following is a specification.

This invention relates to an apparatus for driving a rotary engine actuated by fluid medium supplied by a generator, which permits of varying at any desired instant and at will the number of revolutions of the engine between a minimum determined by the ratio of the volume of the generator (pump) delivering the driving medium to that of the engine, or between zero and a theoretically unlimited maximum.

In carrying out the invention there are employed a rotary distributing device (flow interrupter), an automatic cut-off member (short circuit valve), and an accumulator.

The variation of the number of revolutions of the engine is effected in accordance with the present apparatus by collecting in an accumulator at regularly repeated intervals a regulatable quantity of the driving medium which is continuously supplied by the pump, during which intervals the inlet and exhaust connections of the engine are short circuited, the accumulated part of the driving medium being allowed to pass through the engine when the fluid supplied by the pump is passed through.

It is evident that, when the same quantity of driving medium is supplied to and consumed in the engine in part of a unit of time, the number of revolutions of the piston must increase or decrease with the time allowed for passage of the fluid through the engine. While, according to the known method employing multi-stage engines only definite stages of velocity can be obtained, the present apparatus permits of regulation to any suitable intermediate value between a minimum and a maximum theoretically unlimited *i. e.* to obtain a continuous reduction or increase of the velocity.

The minimum number of revolutions of the engine as set forth is determined by the ratio of volume of the pump delivering the driving medium to that of the engine. If now the pump be fitted with a device constructed in accordance with the specification of my co-pending patent application No.

774,001 (in which substantially the flow interrupter of this case is shown, described and claimed, together with its combination with a pump) which renders it possible to vary at any time the output of said pump between a maximum determined by the capacity of the pump and zero, it is possible to regulate at will and at any desired time the output of the engine between zero and a theoretical unlimited maximum.

The apparatus comprises in addition to an accumulator of usual construction, a rotary distributor (flow interrupter) which is interposed in the pressure pipe an adjustable sleeve which surrounds the distributor, determining the duration of the time interval for the admission of the driving medium into the engine *i. e.*, the time of non-interruption of flow of the driving medium, and therewith the duration of the time interval during which the flow of the driving medium is interrupted or the engine short circuited.

An installation is shown diagrammatically in the accompanying drawings, in which Figure 1 shows the position of the interrupter dependent on the engine; this arrangement permits variation of the number of revolutions of the engine between the minimum output of the same and a theoretical unlimited maximum, the number of revolutions of the flow interrupter, *i. e.*, the number of periods of interruptions, increasing with increase in the number of revolutions of the engine; the position of the movable part of the flow interrupter corresponds to the minimum output of the engine.

Fig. 2 shows a view similar to Fig. 1 the interrupter, however, being operated by the pump supplying the engine so that it rotates independently of an increase or reduction in the number of revolutions of the engine; the position of the movable part of the interrupter corresponds to a number of revolutions of the engine double that involved in the arrangement shown in Fig. 1.

Fig. 3 shows the arrangement of two similar interrupters one of which is connected to the pump and the other to the engine; this arrangement permits variation of the number of revolutions of the engine to any value between zero and a theoretically unlimited amount. Fig. 4 is a cross section and Fig. 5 a horizontal section on the longi-

tudinal axis through the interrupter and Figs. 6, 7 and 8 show in separate views details of the latter.

As shown, in a casing *a* are arranged an annular passage *b* and the distributing chamber *c*. The passage *b* communicates with a connecting branch *d* the chamber *c* with a branch *e*, the said branches serving, according to the direction of rotation, either as inlet or outlet for the driving medium. The passage *b* has a second connecting branch *b*¹ to which is connected the accumulator *S*, hereinafter described, when the same is not directly interposed in the pressure pipe. With regard to the operation of the present arrangement it is immaterial whether the accumulator *S* be connected to the branch *b*¹ or directly to the pressure pipe, since the annular passage *b* forms a part of the pressure conduit.

The passage *b* communicates with the interior of the outer casing *a* by means of ports *i* (three ports in the case shown) while the chamber *c* forms an enlargement of the internal cavity of the casing *a*.

Axially of the casing is mounted the rotary distributor which is arranged as a hollow cone, which is continuously rotated at a rate proportional to the number of revolutions of the engine which it controls; it has for this purpose on one end an extension formed by the shaft portion *g*, which is led to the exterior through the stuffing box *h*, and carries the driving mechanism (belt pulley, friction disk or the like).

The distributor has two rows of ports *k* and *m*. On rotation of the distributor the ports *k* register with and then pass the ports *i*, while the ports *m* continuously connect the interior of the distributor with the chamber *c*. The distribution of the driving medium thus always takes place when the ports *k* and *i* are connected.

Between the distributor *f* and the casing *a* is arranged a sleeve (Figs. 6 to 8) which has corresponding ports, the size of which determines the interval of time during which the ports *k* connect with the ports *i*. Since this interval of time and in consequence the length of the ports (considered in the direction of the circumference) must be variable, the sleeve is formed of two parts *n* and *o* which engage one another by means of tooth shaped projections *r* and *s* directed toward one another in such manner, that in the two extreme positions of the parts in which the edges of the projections lie close together, the sleeve has as many ports *q* as there are ports *i* in the outer casing, while in each intermediate position of the two parts there are double the number of ports *q* and *q*¹ of which however, the half (*q*¹) are covered by solid portions of the wall of the outer casing and therefore remain inoperative.

One part (*n*) of the two parts of the sleeve (Figs. 1 to 7) is adjusted and secured within the outer casing *a* and determines with one edge of its projections the time of opening of the inlet for the driving medium and, by means of a second row of ports *m*¹ produces continuous communication between the chamber *c* and the interior of the rotary distributor *f*. This part *n* may be secured by means of a ring *j* toothed on its circumference which engages the correspondingly cut rim *j*¹ of the sleeve, and secured to the bottom of the casing *a*. The other part of this sleeve (*o*) (Fig. 8) is rotatable and can be operated by means of a lever *t*, mounted on the hollow shaft *g*¹ surrounding the stuffing box *h* and led to the exterior through a second stuffing box *h*¹, which hollow shaft *g*¹ is coupled with the part *o* of the sleeve by means of teeth or the like.

The width of the projections *r* and *s* is so chosen that when in close proximity, they form ports *q* which are of such length (considered in the direction of rotation) relatively to that of the ports *k* in the distributor that on rotation of the distributor interruption of the flow of the operating medium never takes place (Fig. 1); this result can, however, be obtained only when the number of ports *k* in the distributor as illustrated is correspondingly greater than the number of ports in the outer casing so that one port *k* registers with a port *q* in the sleeve before the preceding port *k* leaves the same port *q* of the sleeve. In this position of the sleeve part *o*, the flow interrupting device is inoperative and the engine operates with the lowest velocity of rotation (number of revolutions).

When the part *o* of this apparatus is so adjusted that the length of the port from that edge of the fixed part *n* which determines the inlet amounts only to a part of the former length, for example only to one half (deducting the width of the port *k* Fig. 2), since the generator (pump) delivers always the same quantity of fluid, the engine must use this quantity of fluid within the half unit of time so that it runs at double the number of revolutions.

To this end there is collected within an accumulator *S* that part of the quantity of driving medium which is delivered by the pump during the time in which the flow interrupting device *V* closes the opening, leading to the engine *M*, the accumulator being connected either to a point of the pressure pipe *D* in front of the device *V* or with the passage *b*. The connection between the accumulator *S* and the delivery part *D*¹ of the pressure pipe leading from the interrupter to the engine is only opened by the rotating part *f* when the direct connection between the engine and pressure pipe is open through

105

125

130

the apparatus V. Since the accumulation of the driving medium within the accumulator S always takes place, when the connection with the engine is interrupted, and therefore under correspondingly increased pressure, it is clear, that on subsequent re-opening of the passages both the part of the driving medium directly delivered by the pump and the part flowing away from the accumulator can flow into the engine which therefore can utilize in half of the unit of time the whole quantity of fluid only by rotating at double the number of revolutions.

15 In order that during the time when the flow of driving medium into the engine is interrupted, the same may not become wholly or partly empty and may not produce a vacuum in the delivery part D¹ of the pressure pipe D beyond the apparatus V, which vacuum would prevent the collecting action of the accumulator, this part of the pressure pipe is connected with the pipe R leading the driving medium away from the engine, by means of a pipe L¹ in which is interposed a valve v (short circuit valve) which opens toward delivery part of the pressure. Thus, each time that the distributor f in its rotation interrupts the pipe supplying the driving medium to the engine, a short circuit is formed. Of course this intermittent admission of driving medium into the engine involves a fairly large coefficient of cyclic variation occasioned by the operation in periods in which pressure phases alternate with no pressure phases; to compensate for this suitable gyroscopic masses may be employed.

During the interruption of flow through 40 the apparatus V the stream of driving medium delivered by the pump in constant quantity is collected within the accumulator S. The engine operates however, while short circuited during the same interval of 45 time which represents only a part of a revolution with the consumption of a part of the energy of the masses moved by the same until the interruption of the flow is discontinued, this operation being permitted 50 by the automatic opening of the short circuit valve interposed between the inlet and outlet pipe of the driving medium of the engine.

When, as already mentioned, the adjustment of the sleeve n o of the interrupter is 55 such that the duration of the interruption is equal to the duration of the non-interruption (Fig. 2), as the engine can receive fluid only during the period of non-interruption, and since this time is reduced by 60 one half, and the quantity delivered by the pump for driving the engine remains unchanged the engine can consume the constant quantity only by doubling its velocity.

65 When the engine runs at low speed, the

pressure in the accumulator increases, since more liquid flows into the accumulator than can flow away therefrom; the pressure raised in such manner will naturally increase the velocity of the driving medium. 70 When the engine runs faster, the pressure in the accumulator decreases, since more liquid is taken from the accumulator than flows thereto and the reduced pressure effects reduction of the velocity of the driving medium and therewith reduction in the output of the engine. The latter therefore tends to maintain continuously the same number of revolutions.

The longer the duration of the intervals 80 of the periodic interruptions of the flow the faster the engine runs, and vice versa each reduction of the intervals of the interruptions effects a slower operation of the engine to a point which corresponds to the 85 minimum velocity.

It is evident that the number of revolutions increased in the manner described will attain the theoretical maximum when the length of the passage slot is infinitesimal. 90 Since the sleeve o can be adjusted and secured at any and every intermediate position between the two extreme positions, any desired number of revolutions can be obtained, and that by gradual increase or reduction, so that smooth transition from high to low velocities and vice versa is obtained.

While the rotary distributor, since it forms a single piece, is completely balanced 100 with regard to the forces (pressures) operating in the direction of rotation, the movable part o is not balanced and this movable part is under pressure acting in the direction of the circumference which pressure 105 tends to bring the part o of the sleeve back into the extreme position corresponding to the smallest opening of the inlet slot q. Since these pressures may be of considerable amount, this part of the sleeve must be completely balanced with regard to these moments of rotations, in order to permit of adjustment by hand.

Accordingly a piston w movable within a cylinder x is caused to act on a lever t 115 (Fig. 1) through the intermediary of a rod w'. The surface of the piston opposite to the piston rod is under the action of the pressure in the delivery part D¹ of the pressure pipe which part leads from the interrupter V to the engine M. The area of the piston and the distance between the point of connection of the piston rod to the arm of the lever t and the pivot of the same are so chosen that the product of these two 120 factors is equal to the sum of the pressure faces of the movable part of the sleeve multiplied by the mean distance of these pressure faces from the axis of rotation of the latter. In this manner two equal turning 125 130

moments are obtained which increase or decrease with increased or reduced pressure in the delivery part D¹ of the pipe D, and since they operate against one another, balance one another; in each position of the sleeve, which therefore is completely balanced and can be adjusted easily by hand even with the highest pressures.

As already mentioned, the operation of the interrupter produces a great variation in the motion of the motor, since this motion consists of succeeding full and no pressure phases (periods). The number of periods is increased the smaller the duration of time during which the passage of the driving medium to the motor is opened, since, according to the arrangement shown in Fig. 1, the interrupter V is driven by the motor at a determined ratio.

20 It may be desired to maintain the number of periods of the interrupter constant without affecting the variability of the output. This is obtained according to the arrangement shown in Fig. 2 by moving the interrupter V connected to the motor and controlling the same by means of the pump P which delivers the driving medium and rotates at a constant number of revolutions. When the position of the pump P in relation to the interrupter V does not permit the operation of the latter by means of the pump or permits the operation only by means of intermediate members, the interrupter can be operated directly from an auxiliary engine at a constant number of revolutions.

While the arrangement shown in Figs. 1 and 2 only permits variation of the speed of the engine between the minimum determined by the ratio of the volume of the pump to that of the motor and a maximum, the arrangement shown in Fig. 3 permits variation of the speed of the engine between the given minimum and zero.

45 For this purpose an interrupter V' is connected also to the pump being interposed in a short circuit pipe K connecting the suction pipe L with pressure pipe D, and rotating at a velocity having a fixed ratio to that of the pump rotor as described in the specification of my co-pending application Serial No. 774,001.

This interrupter permits variation of the quantity to be delivered by the pump between a maximum and zero; in this manner gradually reduced quantities of liquid can be supplied to the engine and the output or number of revolutions can be varied down to zero.

60 In the operation of the interrupter a uniform average speed is given. In the period during which the interrupter is closed the driving liquid furnished in a uniform manner by the pump (generator) cannot flow to the motor but will be accumulated in the ac-

cumulator. During this period the fly-wheel has to overcome the resistance of the machinery driven by the rotary motor. In that period during which the interrupter is opened, those parts of the driving medium which during the former period in which the interrupter was closed were accumulated in the accumulator, and also those parts of the driving medium which is furnished from the pump directly during this period (when the interrupter is opened), are led to the motor.

Presuming that the periods during which the interrupter is opened have the same duration as the periods in which the interrupter is closed, viz: half the time of a period when the interrupter is wholly opened, then the motor is driven with twice the number of revolutions because in the pressure periods (during which the interrupter is opened) the motor must consume the same quantity of medium in half the time as when the interrupter is opened. In the periods in which the interrupter is closed (non-pressure periods), the conduit leading the driving medium to the motor is in communication with the conduit leading from the motor by the non-return or short-circuit valve and therefore it is impossible for a vacuum to be produced in the motor chambers or in the delivery part of the conduit which would prevent the collection or accumulative action of the accumulator.

It is to be noted that the periods of the interruption and non-interruption are very short, and that, therefore, it is impossible for the reaction of the machinery driven by the motor to be greater than the action of the fly-wheel and under these circumstances the speed of the motor drum may be assumed as constant.

Having described my invention I declare that what I claim and desire to secure by Letters Patent of the United States is:—

1. In an apparatus of the character described, the combination with a rotary pump for delivering fluid and a rotary motor, of pipes leading from the pressure side of the pump to the motor, a pipe leading the exhaust from the motor, a rotary flow interrupter fitted in said piping, an accumulator connected with said piping, a short-circuit pipe connecting said piping with said exhaust pipe, and a non-return valve arranged in the short circuit pipe.

2. In an apparatus of the character described, the combination with a rotary pump for delivering fluid and a rotary motor, of piping leading from the pressure side of the pump to the motor, a pipe leading the exhaust from the motor, a rotary flow interrupter fitted in said piping and driven by the pump, an accumulator connected with said piping, a short-circuit pipe connecting said piping with said exhaust pipe and a

non-return valve arranged in said short-circuit pipe.

3. The herein-described flow interrupter consisting of a casing having two passages one of which serves as driving medium inlet, the other as driving medium outlet, an accumulator, directly connected to the said casing, a rotary hollow distributor having a ported wall adapted during its rotation to establish communication at intervals between the driving medium inlet and the outlet, and a sleeve disposed between the casing and the rotary distributor, said sleeve consisting of a stationary and an adjustable part, said parts having interengaging tooth-shaped projections and recesses, a hollow shaft on said adjustable part, said hollow shaft extending through the casing, a lever mounted on said hollow shaft, a cylinder, and a piston movable within said cylinder, said piston being coupled with the lever and connected with the pressure pipe of the driving medium.

Signed at Vienna in the Province of Lower Austria, Austria-Hungary, this third day of June, A. D. 1913.
